UNITED STATES PATENT OFFICE.

JOHN DERBOHLLAW, OF NEW YORK, N. Y.

MACHINE FOR MAKING TINSEL THREAD.

SPECIFICATION forming part of Letters Patent No. 364,339, dated June 7, 1887.

Application filed August 11, 1886. Serial No. 210,500. (No model.)

To all whom it may concern:

Be it known that I, JOHN DERBOHLLAW, of the city of New York, in the county and State of New York, have invented certain new and useful Improvements in Machines for Making Tinsel Threads, of which the following is a specification.

The object of my invention is to provide a new and improved machine for making tinsel thread.

The invention consists in the construction and combination of parts and details, which will be fully described and set forth hereinafter, and finally pointed out in the claims.

15 In the accompanying drawings, Figure 1 is a front view of my improved machine for making tinsel. Fig. 2 is a cross sectional view of the same. Fig. 3 is an enlarged detail side view of the tubular spool-holder, the spool on the same, the flier, and the cord passed through the spindle. Fig. 4 is a longitudinal sectional elevation of Fig. 3. Fig. 5 is a detail view of the spindle and bobbin.

Similar letters of reference indicate corresponding parts.

25 On the frame A are fixed a number of spindles, B, for receiving the spools C, on which cotton or other threads are wound. In front of the spools B a bar, D, is provided, in which 30 a series of horizontal tubular shafts, E, are provided, those ends of the tubular shafts opposite those passed through the bar D being pointed, as shown at E', and on said tubular shafts the revolving spool-holders F are mounted, which 35 are provided with pulleys F', in contact with all of which the driving-cord G passes, which is also passed over a pulley, H, mounted on the shaft I², driven by a band, I, passed around pulley I' on the shaft I² from a pulley, J, on 40 the main driving-shaft K, the last having a suitable crank-handle or other suitable actuating device, as shown in Fig. 1. The driving-cord passes over and under the several pulleys F' alternately.

45 Each revolving spool-holder is provided with a flier, L, having two eyes, through which the tinsel thread a is passed, said tinsel thread being wound on a spool, M, mounted on the spool-holder. So that the spool may not revolve on the spool-holder, a spiral spring, O, 50 is provided on the spool-holder, which spring is held in place by a removable collar, P, on

said spool-holder, said collar being held in place by friction. The threads b from the several spools C are passed through the tubular shafts E to the pointed ends E' of the same, and over the pulleys Q, mounted in a row on the shaft R at one side of the machine, said shaft being revolved by a band, R², passing over a pulley, R', on the outer end of the shaft 60 R, and over pulley W² on the shaft W', said shaft being driven by a band, R⁴, passed around pulley R³ on the shaft W' from the pulley R⁵ on the main shaft K.

Some distance below the pulleys Q a row of 65 vertical spindles, S, is provided, which are revolved by means of the band S' from the pulley T on the same shaft with the pulley H. On each spindle S a bobbin U and a flier, V, are provided, one spindle S being provided for each 70 two pulleys Q, the spool-holders being held by any well-known friction devices to prevent them from revolving.

The tinsel is wrapped around the pointed end E' of the tubular shafts E, against the inside of which pointed end the thread that passes through the tubular shaft rests, so that as the said thread passes from the pointed end the tinsel is wound around it.

The operation is as follows: By turning the 80 shaft K the several spindles, pulleys, spools, &c., are revolved, and the thread from each spool C, in passing the pointed ends E' of the corresponding tubular shaft E, is surrounded by tinsel, which is wound spirally on the said 85 threads. The end of the spindle is made pointed, so that the thread can lie snugly up against the same and the diameter of the coils of tinsel passed around the ends of the spindles be as short as possible. The wound threads, 90 which are passed over the pulleys Q, are then doubled, and then the doubled threads are passed through the tubular ends of the spindle S, passed through apertures in the sides of the shaft, and by the fliers V are wound upon 95 suitable bobbins placed on the said spindles S. The thread b is thus wound with tinsel, and the wound or covered threads are doubled and twisted and wound upon the bobbins U in a single operation.

Having thus described my invention, I claim as new and desire to secure by Letters Patent—

1. The combination, with a tubular shaft provided at one end with a tapered pointed

projection, forming a continuation of one side only of said tubular shaft, of a revolving spool-holder mounted on said tubular shaft and a flier on the spool-holder, substantially as shown and described.

2. The combination, with a tubular shaft having one end pointed, of a revolving spool-holder on said shaft, a flier on the spool-holder, a spring surrounding the spool-holder at one end of the spool, and a collar on the spool-holder for the purpose of holding the spool and spring in place, substantially as shown and described.

3. The combination, with a frame, of a series of spindles for receiving spools, tubular pointed shafts in front of said spindles, revolving spool-holders and fliers mounted on the tubular shafts, and revolving spindles provided with fliers for receiving the threads passed through the tubular shafts carrying the revolv-

ing spool-holders, substantially as shown and described.

4. The combination, with a frame, of a series of spindles for receiving spools, a row of pointed tubular shafts in front of the spools, 25 revolving spool-holders provided with fliers mounted on the tubular shafts, a row of pulleys in front of the tubular shafts, one pulley being provided for each tubular shaft, and a row of spindles below the above-mentioned row of 30 pulleys, one spindle being provided for each two pulleys, substantially as shown and described.

In testimony that I claim the foregoing as my invention I have signed my name in presence of two subscribing witnesses.

JOHN DERBOHLOW.
